UNITED STATES PATENT OFFICE.

OLIVER BANGS, OF NEW HAVEN, CONNECTICUT.

STREET-RAILWAY SWITCH.

SPECIFICATION forming part of Letters Patent No. 317,282, dated May 5, 1885.

Application filed February 2, 1885. (No model.)

To all whom it may concern:

Be it known that I, OLIVER BANGS, of New Haven, in the county of New Haven and State of Connecticut, have invented a new Improvement 5 in Street-Railway Switches; and I do hereby declare the following, when taken in connection with accompanying drawings and the letters of reference marked thereon, to be a full, clear, and exact description of the same, 10 and which said drawings constitute part of this specification, and represent, in—

Figure 1, a plan view of the switch, showing its relation to the main track, the switch in its normal condition or as forming a continuous main track; Fig. 2, the switch as turned automatically by the cars coming from the approaching track onto the main track.

This invention relates to an improvement in the switch such as employed in turn-outs 20 on street-railways.

As more generally constructed, the rails are made rigid at the switch, the wheel on one side running over the rail as it comes from one track onto the other, and so as to drop down 25 when it reaches the track it is approaching, which produces not only an unpleasant jolting to the car, but brings great wear upon the flange of the wheel as well as upon the switch.

The object of my invention is to overcome 30 these difficulties; and it consists in leaving a space between the end of the outside approaching rail and the end of the corresponding rail on the main track, the continuation of the main rail from the said end of the main track 35 made elastic, and constructed with a block to fill the said recess between the end of the approaching rail and the said end of the main rail, the upper surface of the said block constructed with a longitudinal groove corresponding substantially to the flange of the 40 wheel, combined with a guard-rail inside the opposite rails, as more fully hereinafter described.

A represents the inside rail of the main track, 45 and B the outside rail of the same track; C, the outside rail of the switch or turn-out, and D the other rail of the switch or turn-out. In the illustration I show a switch or turn-out as the main track coming from the left and the 50 switch coming from the right—an arrangement common in single-track street-railways, the

approach being indicated by arrows. The term "inside" is applied as indicating the left-hand rail from the direction of the approach. Between the end of the approaching rail C and the end of the inside rail, A, of the main track I leave a recess.

E represents a continuation of the rail of the main track. It is fixed at a point distant from the end of the rail A—say as at a—but from that point to the end of the rail A it is free, and is elastic, so as to be moved transversely, and return. At its end next the main rail it is constructed with a block, F, which fills the recess between the end of the approaching rail C and the corresponding end of the main rail A. On the uppersurface this block is constructed with a groove, b, into which the flange of the wheel may run without bearing upon the bottom of the groove. The rail D 60 terminates alongside the rail B, but so as to leave an opening, d, between them, and through which the flange of the wheel may run. Inside the rails D and B, at their intersection, a guard-rail, G, is arranged, curving toward 65 the opposite side. As the cars approach from the left, one wheel will follow the rail A and readily pass onto the spring-rail E as a continuation of the said rail A, while the other wheel on the rail B will follow that rail, and the 70 cars readily pass along the main track without interference, or effect from the switch, the rails being practically continuous, and as seen in Fig. 1. Coming from the opposite direction on the rails CD, the one wheel follows 75 the rail D, its flange striking the guard-rail G to hold it against the rail D and lead it onto the rail B. This guard draws the opposite wheel against the outside of the spring-rail E, and because the other wheel is held by 80 the guard G and cannot be drawn toward the opposite side the wheel upon that opposite side, bearing against the outside of the spring-rail E, turns that rail inward, bringing the 85 groove inward, and so that the part of the block F outside the groove comes into line with the approaching track C and the main rail, and practically forms a continuation of the same, as seen in Fig. 2, so that the wheel on the track C passes along the block F and 90 onto the rail A, as if upon a continuous track. So soon, however, as the wheel passes from

the spring-track E, the elasticity of the said spring-track forces it back into its normal position, and into line with the main track, a stop, d' , being provided to arrest the return of 5 the spring portion of the track when it shall have arrived at its proper position with relation to the track A. Thus the cars coming from the left pass to the right as if upon a continuous track, and on the return, as the approaching rails come to the main rail, the switch is automatically brought into line with the approaching rail and the main rail, so that the cars come from the switch onto the main rail again as if upon a continuous track. 10 It will be understood that a like switch is provided at the opposite end of the turn-out. By this construction the jolting experienced in the usual construction of the turn-outs and switches is avoided. This representation of 15 the switch as applied to a turn-out will be sufficient to illustrate the application of the invention to switches at other points. It will be 20

understood that the spring-rail is to be made fast to a metal plate, which extends to form a support for the ends of both the rails A and 25 C, and upon which plate the spring-rail will move, and as shown in the drawings.

I claim—

The herein-described switch for railroads, consisting in the transversely-elastic rail E, 30 forming a continuation of the main rail A, constructed with a block, F, at its free end, to abut against the end of the said main rail A, and set into a space between the end of the main rail and the approaching rail C, the said 35 block F, constructed with a groove, b, in its upper surface, combined with corresponding opposite rails, B and D, and the guard-rail G at the intersection of the said rails B and D, substantially as and for the purpose described. 40

OLIVER BANGS.
